2,130,655

MANUFACTURE OF WARP GOODS

Paul Schönfeld, Chemnitz, Germany

Application August 16, 1937, Serial No. 159,399
In Germany July 21, 1937

2 Claims. (CL 66—86)

This invention relates to a method of producing transversely ribbed warp fabric by means of two lapping machines on a warp loom having only one row of needles, and constitutes an improvement of Patent No. 2,012,355, of August 27, 1935.

The purpose of the method covered by this patent is to produce ribbed warp goods on a frame having only one row of needles by working two sets of threads, one of which forms the usual ground fabric which is then ribbed by the second thread group. The warp fabric produced under the mentioned patent differs from ribbed goods made on machines having two rows of needles by being transversely ribbed.

According to the mentioned patent, the lower lapping machine operating the second thread group carries out only underlaying operations to form ribs by being alternately racked in the same direction as the upper machine and in the opposite direction thereto. It has been found, however, that goods made in this manner are relatively thin for the reason that the threads of the lower lapping machine form only loose loops which extend through the fabric formed by the threads of the upper machine. Such goods are therefore not suited for all purposes.

The invention aims at eliminating this drawback by causing the lower machine to carry out overlaying operations when it is racked in a direction opposite to the upper machine.

In this way the threads of the lower machine will partly help to form loops to fill the goods without appreciably interfering with the formation of ribs which, as has been ascertained, are produced chiefly by the alternate racking of the lower machine once in the same direction as the upper one and then again in a direction opposite to the latter. Only where the two lapping machines are racked in the same direction is it necessary to retain the underlying operations of the lower machine, in which case of course an overlay could be put in also.

By way of example, the invention is illustrated in the accompanying drawing which shows a lapping diagram.

As in the mentioned patent, the threads 1 are gathered in the upper lapping machine and the

threads 2 in the lower machine. The upper machine laps a ground fabric which in the example shown has the form of a simple tricot lap. The lower machine places the thread 2 under three to the left in the first course, in the second course under three again but to the right and in the third course under three but to the left again. In the fourth course the lower machine operates under two to the right and over one to the left and in the fifth course under one and over one to the right. In the sixth course the thread 2 of the lower machine is not racked laterally, whereupon the cycle starts again, so that the mode of racking of the lower machine is repeated every six rows.

On the left of the diagram the figures 1 to 6 designate the courses. It is important that the lower machine in the courses 1 to 4 is racked in the same direction as the upper machine, but opposite to it in course 5. In the fourth and fifth courses the threads 2 form meshes which are laid over the needles, which brings about the desired filling of the fabric to such an extent that the threads of the lower machine need not be drawn in completely for filet work but only partly as for instance one half.

It is to be remarked that for lapping machines the one which is the lower machine is the one to which the needles are applied when the lapping machines are on the side where the fabric is removed from the needles.

I claim:—

1. A method of producing transversely ribbed warp fabric by means of two lapping machines on a warp loom having only one row of needles, comprising lapping a ground fabric with the upper machine and carrying out underlaying operations with the lower machine, the lower machine being alternately racked once in the same direction as the upper machine and then again in a direction opposite thereto and carrying out overlaying operations when racked in opposite direction to the upper machine.

2. A method according to claim 1, in which the lower machine has the threads arranged for filet work.

PAUL SCHÖNFELD.
